Application March 17, 1958, Serial No. 722,028

2 Claims. (Cl. 200—117)

The present invention relates to thermal relays and has particular reference to a miniaturized reliable structure for applications involving a wide range of environmental conditions such as temperature, vibration and shock.

Devices of the character to be described may be employed in cooperation with numerous electrical circuits to activate any desired mechanism on a one-shot basis where performance capable of high reliability is required. A further requirement for the intended usage is that subject devices be miniaturized without in any way sacrificing any of the reliability features.

It is an object of the present invention to provide a miniaturized thermal relay of simplified and ruggedized design.

A further object is the provision of a thermal relay having a high degree of reliability under adverse environmental conditions.

The invention features a plurality of sets of conductive contacting members which in the final state of operation mate with one another to provide a conductive path to either trigger or close related electrical circuitry. Initially, one set of contacting members are supported under tension by a fusible element which is rapidly burned-out by passage of an electrical current through suitable leads. The overall relay structure is hermetically sealed in a dielectric enclosure with external leads extending therethrough for connection to desired circuitry. Suitable inert atmospheres such as dry nitrogen, argon and helium may be introduced into the enclosure or it may be evacuated. The advantages include non-critical adjustments of contact members, ease and speed of assembly by use of stamped components and self-alignment of the structure. The provision of parallel conductive paths assures the high reliability of operation. Further, selection of appropriate high temperature metals and method of assembly has resulted in reliability of operation under severe conditions of temperature, vibration and shock.

Further objects, features and advantages will be apparent after consideration of a detailed description of an illustrative embodiment and the accompanying drawings, in which:

Fig. 1 is an enlarged perspective view with a portion of the envelope broken away;

Fig. 2 is a detailed cross-sectional view;

Fig. 3 is an exploded view of the internal contact assembly structure; and

Fig. 4 is an enlarged view of a portion of the illustrative device to reveal structure for mounting of the fusible and tensioning elements.

Referring now to the drawings, in particular Figs. 1 and 2 the illustrative embodiment comprises an envelope 1 with glass stems 2 and 3 sealed at the ends thereof. Each stem defines a hub portion 4 and 5 with electrical leads extending therethrough. Leads 6 and 7 are supported by stem 2 and another pair of leads 8 and 9 are supported by the oppositely disposed stem 3. If desired other types of stem enclosures such as the dielectric reen-

trant or butt seal types or metallic headers may be employed at the ends of envelope 1 in the manner well known in the art.

An upper contact assembly 10 may be fabricated from 5 a flat stock of a metal, such as beryllium copper or molybdenum and may also be plated with a coating of any highly conductive metal, such as gold. Contacting assembly 10 is provided with split rim section 11 and a pair of arms 12 and 13 depending downwardly and then 10 angularly therefrom to define a gap therebetween. Rim 11 is formed in such a manner that it will firmly engage the hub portion 4 to which it is secured.

Another or lower contact assembly 14 fabricated from 15 a similar metal as assembly 10 is mounted on hub portion 5 of the bottom stem 3. A rim 15 to firmly grip the hub portion is provided and arms 16 and 17 extend therefrom so as to contact one another under tension. To assure 20 good electrical contact when the relay device is in the fired stage of operation, the flat surfaces adjacent to the ends of arms 16 and 17 may be provided with embossments 18. A third arm 19 is defined in assembly 14 for use in connection to external leads in a manner to be described hereinafter.

The operation of the illustrative thermal relay device 25 and the method of assembly will be better understood by referring now to Figs. 3 and 4. It will also be possible to follow the connection of the external leads to internal contact members by means of dotted lines shown in Fig. 3. Lead 6 is electrically connected to arm 19 and lead 30 7 is secured to contact assembly 10. These leads, therefore, provide means for connection to an external circuit. With the arms 16 and 17 of contact assembly 14 in contiguous relationship by means of the fusible element and tensioning arrangement to be described, the 35 contacting arms will be positioned in the space defined between upper contact arms 12 and 13. This represents the initial state of the device and as a result no conductive path would be defined between leads 6 and 7. After removal of the tensioning means arms 16 and 17 40 snap apart and mate with upper arms 12 and 13 to complete the circuit.

The fusible element and tensioning means will now be described, reference being directed to Fig. 4. The leads 45 8 and 9 are formed at their inner ends with right angular extensions oppositely disposed as at 20. An insulator 21 of a material such as a ceramic is then secured to extensions 20 by means of a fusible wire 22 such as for example a wire of a material, commonly referred to by the trade-mark Karma, with several turns around each lead 50 extension and the ends secured as by welding. An axial passageway 25 in insulator 21 extending parallel to extensions 20 provides means for introduction of a tensioning wire 23 which is passed through opening 24 in the arms 16 and 17 several times and then secured at the 55 ends thereof to said arms. In an illustrative embodiment a nickel ribbon .003 thousandths thick and .010 thousandths wide was employed because of the ease in spot-welding the ends thereof to the arms.

In the method of assembling the device, the insulator 60 21 with the tensioning wire extending therethrough and secured to arms 16 and 17 is pulled downward to bring the ends of said arms in contact. The fusible wire 22 is then secured around the insulator and extensions 20 of leads 8 and 9. Hence by the passage of an electrical current through leads 8 and 9 the fusible wire will be burned out to thereby result in arms 16 and 17 snapping apart to mate with arms 12 and 13 of the upper contact assembly. With the structure disclosed high reliability has been attained in relays required to operate on a one-shot basis. Further, such devices have been fabricated having an overall length of only $\frac{3}{4}$ of an inch

and a diameter of only $\frac{1}{4}$ of an inch which is highly desirable, particularly in air-borne applications. Other possible fusible element arrangements will occur to those skilled in the art. For example, an insulator in the form of a grooved pulley could be suspended by means of a tensioning wire between the contact arms 16 and 17. A fuse wire would then ride over the pulley and be secured to the ends of the leads to define the conductive path for passage of a burn-out current. A further modified insulator may be provided in the form of a hook and eye combination with the hook portion coated with an insulating material such as saueriesen glass. The burn-out wire would then be positioned over the hook while the tensioning wire would extend through the eye portion.

In addition the invention may be provided with an exhaust tubulation introduced in either of the end stems. Either evacuation or filling of the envelope with an inert atmosphere would then be possible. Argon, helium or dry nitrogen have been successfully employed with the latter displaying excellent hold-off voltage characteristics.

What is claimed is:

1. A thermal relay device comprising an envelope hermetically sealed at the ends thereof by stem enclosures, first and second oppositely disposed metallic contact assemblies supported by said stem enclosures, said first contact assembly comprising a pair of dependent arms defining an open gap therebetween, said second contact assembly comprising a pair of dependent arms held in contiguous relationship by tensioning and fusible means with the ends of said fusible means connected to electrical leads extending through one of said stem enclosures, said fusible means being rapidly severed by passage of an electrical current therethrough to thereby cause said con-

tiguous arms to spring apart and mate with the arms of said first contact assembly and electrical leads extending through the other of said stem enclosures for connection to said first and second contact assemblies to define a continuous conductive path when said contact assemblies are in mating relationship.

2. A thermal relay device comprising an envelope hermetically sealed at the ends thereof by stem enclosures having inwardly disposed hub sections, first and second contact assemblies of a highly conductive resilient metal, said first contact assembly comprising a split-rim section girdling one of said hub sections, a pair of arms extending from said rim section with the ends thereof spaced apart to define a gap therebetween, said second contact assembly comprising a split-rim section girdling the oppositely disposed hub section, a pair of arms extending from said rim section with the ends of said arms held in contiguous relationship by tensioning means and a fusible wire, electrical leads extending through the hub portion supporting said second contact assembly with said fusible wire being connected to said leads, said fusible wire being rapidly severed by passage of an electrical current therethrough to thereby cause said contiguous arms to spring apart and mate with the arms of said first contact assembly and electrical leads extending through the opposite hub portion for connection to each of said contact assemblies to define a continuous conductive path when said contact assemblies are in mating relationship.
